UNITED STATES PATENT OFFICE.

WALTER P. MURPHY, OF CHICAGO, ILLINOIS, ASSIGNOR TO P. H. MURPHY COMPANY,
OF PARNASSUS, PENNSYLVANIA, A CORPORATION OF PENNSYLVANIA.

STEEL CAR-ROOF.

1,250,205.

Specification of Letters Patent. Patented Dec. 18, 1917.

Application filed November 6, 1915. Serial No. 59,938.

To all whom it may concern:

Be it known that I, WALTER P. MURPHY, a citizen of the United States, and a resident of the city of Chicago, in the county of Cook and State of Illinois, have invented a new and useful Improvement in Steel Car-Roofs, of which the following is a specification.

This invention relates to steel freight car construction and particularly to the car end and roof construction; and has for its object the strengthening of the roof and the prevention of sweating or collection of moisture on the under side of the roof.

The invention consists in improvements in roofs of the type illustrated in my Patent No. 1,133,495, dated March 30, 1915, wherein the roof sheets span the car from eaves to eaves and have their side margins flanged up and riveted together. The invention also consists in the end plate construction, and in the means of attachment of the roof to the side plates and end plates.

Further objects and details of the invention appear in connection with the following description of the several embodiments of the invention illustrated in the accompanying drawings; and what the invention comprises is particularly claimed in the appended claims.

In the drawings, wherein the same reference characters designate the same parts in the several views,

Figure 1 is a plan view of a portion of the end of a car embodying one form of the invention;

Figs. 2 and 3 are an end elevation and a side elevation, respectively, of the same;

Fig. 4 is a transverse cross-section of the same on the line 4—4 in Fig. 1, looking toward the end of the car;

Figs. 5 and 6 are longitudinal cross-sections of the same on the lines 5—5 and 6—6, respectively, in Fig. 4, looking in the direction of the arrows;

Fig. 7 is a transverse cross-section of the roof at the eaves, showing a modified form of attachment to the side plate;

Fig. 8 is a longitudinal cross-section of the roof at one end of the car, showing a modified form of end plate and attaching means for the roof;

Fig. 9 is a view similar to Fig. 7, of another modification of the invention, show-

ing an I-shape seam cover, a wood lining, and drain channels beneath the seams;

Fig. 10 is a longitudinal section of the roof shown in Fig. 9, taken at the eaves on the line 10—10 in Fig. 9, looking in the direction of the arrows;

Fig. 11 is a longitudinal cross-section through the roof at the ridge, further illustrating the modification shown in Figs. 9 and 10; and

Figs. 12 and 13 are detail views of another modification of the invention, Fig. 12 being a transverse section of the roof at the ridge, showing a portion of the seam in side elevation, and Fig. 13 being a cross-section of the same on the line 13—13 in Fig. 12.

In Figs. 1 to 6 of the drawings, a roof embodying the invention is shown applied to a steel frame box car having Z-bar side plates 11, but it may be applied to other forms of car body. The end plate 12 is a pressed metal member having a vertical web portion 13 extending from side to side of the car and riveted to the corner posts 14 at its ends. The ends of the web 13 are offset outwardly to permit the end posts to lie flush on the inside with the inner face of the web. The top edge of the end plate conforms to the arched shape of the roof, and has a lateral flange 15 extending inwardly under the roof and riveted to the top flanges of the side plates 11 at its ends. The top flange 15 grows wider from the middle of the end plate to the ends, the wide ends enabling rigid connection to be made to the side plates in order to provide a lateral brace for the top of the car at the corners to keep it from being distorted out of square. The lower margin of the middle portion of the vertical web 13 is flanged out and down to form a long hood 16 projecting out from the end plate across the middle of the end of the car. The hood has its greatest outward extent at the middle of the car, and narrows in toward the corner posts. It covers the upper ends of the end posts 17, and the depending flange 18 of the hood fits down outside of the outer flanges of the end posts at their top ends and is riveted thereto. The inner flanges of the end posts 17 are flush with the inner faces of the end posts and web portion 13 of the end plate,

whereby wooden planks 19, or other suitable

end sheathing, can be laid flush against the inside of the corner posts and end posts up to the roof if desired. Preferably the top edge of the end planking 19 is spaced below the top of the hood 16 in order to provide for ventilation at the end of the car.

The roof is made of heavy metal roof sheets 20 which are arranged crosswise of the car, spanning its width from eaves to eaves, and supported at their eaves ends on angle iron eaves strips 21. The side margins of the roof sheets are bent up, forming straight flanges 22 along both sides of each sheet. The flanges 22 of adjacent roof sheets are arranged in juxtaposition, and are covered by inverted U-shaped seam covers 23, which are riveted along their lower edges to the flanges of the roof sheets. The seam covers extend from eaves to eaves, and their ends are bent down over the ends of the joints between the roof sheets. The seam covers are of varying height, being highest at the middle of the car and decreasing in height toward the eaves. The under surface of the roof sheets may be coated with ground cork, magnesia, or other suitable heat insulating material, if desired.

The ends of the roof sheets are spaced above the tops of the side plates 11, and project over their outer edges. The angle shape eaves strips 21 have their horizontal flanges spaced above the side plates, with their vertical legs down, extending alongside of the vertical webs of the side plates on the outside thereof and riveted thereto, with a narrow space intervening. Spacing washers 24, which surround the rivets between the eaves strips and side plates, space the eaves strips away from the side plates in the construction shown in Figs. 1 to 6. This space between the eaves strips and side plates provides for ventilation, and permits water which may condense on the under sides of the roof sheets to drip off over the side plates.

At the ends of the car the roof sheets are spaced above and project over the tops of the end plates, and are riveted to angle iron end strips 25 which extend across the end of the car outside of the vertical webs 13 of the end plates. The vertical legs of the end strips 25 extend down alongside of the webs 13 of the end plates, with a space intervening, and are riveted thereto. Spacing washers 26 may be used to maintain the end strips at a sufficient distance from the end plate to provide for ventilation under the ends of the roof. The spaces between the eaves strips 21 and side plates 11, and those between the end strips 25 and end plates 12, provide sufficient leeway to accommodate slight variations in the dimensions of the roofs and car bodies and permit the roofs to be readily applied to the cars by the use of spacing washers of suitable thickness.

The running boards 27 are arranged lengthwise of the car at the ridge, above the tops of the seam covers 23, and are securely bolted to metal running board saddles 28. The running board saddles have saddle shaped middle portions, and each saddle is mounted astride of a seam cover at the ridge and has two downwardly projecting lugs or ears 29, one near each end, which are riveted to opposite sides of the seam cover at equal distances on each side of the ridge line. This arrangement permits the running board saddles to be removed by twisting them sideways out from under the running boards. The ends of the running boards project over the ends of the car and are bolted to plates 30, which are supported from the end plates 12 by means of brackets 31. The brackets 31 are bolted to the running boards and plates 30, and are riveted to the hood portions 18 of the end plates.

In the modification of the invention shown in Figs. 7 and 8, the eaves strip 32 and end strip 33 which support the edges of the roof sheets 20 are angle irons, and have portions 34 of their vertical legs offset inwardly to bear against the vertical webs of the side plate 35 and end plate 36, thereby dispensing with spacing washers. The under surface of the roof is covered with a heat insulating lining 37 of paper or other suitable material, which is stuck on to the roof sheets with glue or other adhesive substance.

In the modification shown in Figs. 9, 10 and 11, the top of the seam cover 50 is flattened out sideways, and with the lateral flanges along the bottoms of its side walls, an I-section supporting member for the joint is formed which is light and strong. A double trough shaped pressed metal member 51, having its middle wall 52 of double thickness and extended up above the side walls, is arranged beneath each joint, with the middle wall riveted between the flanges 22 of the roof sheets 20. The ends of the troughs or channels project over the tops of the side plates, and empty into the spaces between the eaves strips 21 and the side plates. A lining of thin boards 53 is arranged beneath the roof plates. The boards 53 run crosswise of the car, their ends being supported on wood filler strips 54 which are bolted on top of the side plates. The lining boards 53 are supported at the ridge on the side flanges 56 of a channel shape ridge strip 55 or purlin which extends lengthwise of the car and is riveted to the under sides of the trough shaped members 51, as shown in Fig. 11.

In the modification shown in Figs. 12 and 13, the lining boards 53 run crosswise of the car and are supported at the ridge by rods 57, the ends of which are supported by hangers 58. These hangers are small metal plates which are riveted between the flanges 22 of

the roof sheets 20 at the middle of the car, and which project below the roof sheets and sheathing and have holes through them to receive the ends of the rods 57.

5 Other modifications of the form and arrangement of the parts may be made in view of the foregoing description of the invention; and the invention is not restricted to the forms and arrangements shown in the 10 drawings.

I claim the following as my invention:

1. An end construction for box cars provided with steel roofs comprising an end plate having its top edge shaped to conform 15 to the roof, and a strip supported thereby and spaced therefrom constituting a fascia, the upper edge of said strip being above the top edge of said end plate and rigidly secured to the roof sheets.

20 2. An end construction for box cars provided with steel roofs comprising an end plate having its top edge shaped to conform to the roof and provided with a lateral flange extending inwardly, a strip spaced above 25 said flange and having an offset lower portion supported at intervals along the upper edge of the end plate, and roof sheets spaced above and overhanging said end plate and secured to said strip.

30 3. An end support for a steel box car roof, said support comprising a strip of angle shape bent to conform to the roof, the vertical leg being adapted for attachment to the end plate of the car and the horizontal leg being adapted for attachment to the end of the roof, said strip being provided with spacing means along its lower edge adapted for holding it away from the upper edge of the end plate.

40 4. A car having side plates and end plates, and a metal roof spaced above said side and end plates, said roof resting upon strips which are secured along its edges and which are supported by said side plates and end plates, said strips being spaced from said side and end plates to provide openings for ventilation along the sides and ends of said car.

50 5. A car having side plates and end plates, and a metal roof spaced above said side and end plates, said roof having depending strips secured along its edges, said strips being supported by said side plates and end plates and spaced therefrom to provide openings for ventilation along the sides and ends of said car.

60 6. A car having end plates, and a metal roof spaced above and overhanging said end plates, said roof having strips secured along its overhanging ends supported by said end plates and spaced therefrom to provide openings for ventilation along the ends of said car.

7. In combination with a car roof, roof sheets spaced above the side plate at the

eaves, and an eaves strip comprising a lengthwise extending portion spaced from the side plate and secured to the ends of the roof sheets, and a series of offset portions integral therewith secured to the side plate 70 for spacing said roof sheet supporting portion away from said side plate.

8. In combination with a car roof, an eaves strip comprising a horizontal top portion spaced above the side plate to support the 75 ends of the roof sheets, and a depending flange extending lengthwise of said strip and having a series of offset portions integral therewith secured to the side plate for spacing said flange and roof sheet supporting 80 portion away from said side plate.

9. A metal running board saddle for car roofs having outside ribs, said saddle consisting of a top plate adapted to support the running boards, a central saddle portion 85 adapted to rest upon the top of a rib, and depending lugs arranged one at each end on diagonally opposite sides of the saddle portion, said lugs being adapted to be secured to opposite sides of a rib by horizontal fastenings, whereby said saddle can be removed by twisting it out from under said running boards on severing said fastenings.

10. A metal running board saddle for car roofs having outside ribs with enlarged tops, 95 said saddle consisting of a top plate adapted to support the running boards, a central saddle portion adapted to rest upon the top of a rib, and depending lugs arranged one at each end on diagonally opposite sides of 100 the saddle portion, said lugs being bent in and down and adapted to be secured to opposite sides of a rib below its top, whereby said saddle can be secured in place and removed by twisting it crosswise of a rib.

11. A car roof comprising metal roof sheets extending from eaves to eaves and having upstanding flanges along their side margins, and cover strips arranged over said flanges and riveted thereto through their sides, said cover strips having enlarged heads, and metal running board saddles supported on the tops of the cover strips and each having two fastening lugs arranged one at each end on opposite sides of the saddle portion, said lugs hooking under the heads of said cover strips and being secured to their sides to retain said saddles in place.

12. A car roof having self-supporting roof sheets spanning the car from eaves to eaves, the side margins of said roof sheets being flanged and riveted together, trough members arranged below said riveted flanges, said trough members having upstanding webs secured between said riveted flanges, and means for supporting the ends of said roof sheets and troughs clear of the sides of the car, said means covering the ends of said troughs and being spaced therefrom to protect them from the weather.

13. A car roof having self-supporting roof sheets spanning the car from eaves to eaves, the side margins of said roof sheets being flanged and riveted together, trough members arranged below said riveted flanges, said trough members having up-standing webs secured between said riveted flanges, and means for supporting the ends of said roof sheets and troughs clear of the sides of the car, said means being arranged below the ends of the roof sheets and outside of the side walls of the car whereby each constitutes a drip edge and protection for the ends of said troughs.
14. A car roof having self-supporting roof sheets spanning the car from eaves to eaves, the side margins of said roof sheets being flanged and riveted together, trough members arranged below said riveted flanges, said trough members having up-standing webs secured between said riveted flanges, wooden lining arranged in sections
- below said roof sheets between said troughs from eaves to eaves, and means for supporting the ends of said roof sheets and troughs clear of the sides of the car, said means covering the ends of said lining sections to protect them from the weather.
15. A car roof having self-supporting roof sheets spanning the car from eaves to eaves, the side margins of said roof sheets being riveted together, trough members arranged below said riveted margins and riveted to said roof sheets, said trough members constituting transverse stiffening members for said roof, and means for supporting the ends of said roof sheets and troughs clear of the sides of the car, said means covering the ends of said troughs and being spaced therefrom to protect them from the weather.

Signed at Chicago, Illinois, this third day of November, 1915.

WALTER P. MURPHY.
